ARTIFICIAL LEG

William T. Carnes, Kansas City, Mo., assignor to
 Carnes Artificial Limb Company, Kansas City,
 Mo., a corporation of Missouri

Application April 14, 1930. Serial No. 444,067

7 Claims. (Cl. 3—6)

This invention relates to artificial limbs. One of the objects of the invention is to produce an artificial foot capable of simulating all movements which occur with the natural foot in walking, and which avoids the transmission of shock to the stump in the event the wearer's weight is imposed suddenly on the foot, which operates noiselessly or without squeaks, is waterproof, and is of light weight yet strong and durable.

10 With this general object in view, the invention consists in certain novel and useful features of construction and combinations of parts as herein-after described and claimed; and in order that it may be fully understood, reference is to be had to the accompanying drawing, in which:

Figure 1 is a central vertical longitudinal section of an artificial foot embodying the invention.

Figure 2 is a horizontal section on the line 20 IX—IX of Figure 1, with sheath omitted.

Figure 3 is a vertical section taken on the line X—X of Figure 1.

Figure 4 is an inverted plan view of the shank or lower leg portion.

25 Figure 5 is a detail perspective view of the metal wear plate of the upper member of the ankle joint.

Figure 6 is an inverted plan view of a plate forming the top of the body portion of the foot 30 and also forming the socket portion of the ankle joint.

Figure 7 is a top plan view of the sole plate of the foot.

Referring now to the drawing it will be noted 35 that the lower leg portion 1 is hollow and terminates in a reduced depending portion providing a downwardly-facing shoulder 22 and the lower leg portion is provided with a downwardly-flaring opening 23 near its rear periphery and forward thereof with a depending hemispherical ankle-joint portion 24. The lower leg portion 1 is generally hollow for lightness, is preferably of wood or equivalent material, and the hemispherical ankle-joint portion has a correspondingly

40 shaped metal sheath 25 flanged at its upper margin and secured through the flange portion by screws or otherwise to the lower end of the reduced pendant extension, the lower end of the leg portion rearward of the ankle-joint portion

45 being flat and disposed in approximate radial relation relative to the axis of the ankle-joint portion.

A metal cup 26 receives and is disposed concentrically of the ankle-joint portion, the internal diameter of the cup being somewhat larger

than the external diameter of the metal sheath 25, and containing a leather or equivalent lining 27 so that the ankle-joint movements may occur without the noise or squeak that might be attendant upon a metal to metal contact, especially if the foot has become slightly worn after a long period of service.

The metal cup portion of the ankle-joint fits in a corresponding depression provided in a felt or equivalent compressible foot portion 28 which is flat at its upper side rearward of the ankle-joint and normally stands in a rearwardly diverging relation to the opposing overlying end of the leg portion. The metal cup is provided with a rearward extension 29 fitting down upon the flat upper portion of the foot and with a downwardly and forwardly extending front portion 30 fitting squarely upon the foot portion over what may be termed the instep thereof and terminating slightly short of the plane of the metatarsus joint of the natural foot, and the marginal portion of the metal plate is provided with a depending flange 31 which extends completely around the plate except at its front end, and said plate including the cup portion is preferably vulcanized to the compressible or felt foot portion. The flat rear portion 29 is provided with an opening 32 registering with a vertical opening 33 in the foot portion.

A sole plate 34 of metal or equivalent material underlies the rear half of the foot and is flanged upward marginally at 35, except at its front extremity, to snugly receive the overlying portion of the foot and heel portion thereof, and said plate is provided with an opening 36 and with two inverted V-shaped spaced bearing lugs 37 projecting up into the foot portion, the space between said lugs coinciding or registering with the opening 33, and fitting in said bearing lugs is a cross pin 38 to which the lower end of a non-elastic but flexible cord 39 is attached, the said cord extending up through openings 33, 32 and 23, and being secured at its upper end to a cross pin 40 secured in the leg portion, the arrangement being such that the cord substantially limits forward hinge movement of the leg portion relative to the foot portion and at the same time permits of limited lateral rocking and twisting or rotary movement of the leg portion relative to the foot portion. The rubber shoe acts to hold the leg portion in such position that the leg shall have no lost motion up and down relative to the foot portion, thereby avoiding any shock or jar incident to sudden or excessive downward pressure imposed on the foot portion, such as

85

90

95

100

105

110

might occur when the wearer steps down from an elevated point, as in coming down a stairway or the like. In such action it is intended that the excessive force applied upon the joint 5 shall be absorbed by a gradual compression of the foot portion.

The front end of the sole plate, if not cemented or perhaps even if cemented to the foot portion is preferably fastened to the latter by 10 one or more rivets or screws 41, the upper heads of the rivets or screws being countersunk in the foot portion.

A shoe 42 of rubber fabric or the like possessing great resilience and at the same time utility 15 and durability and of course water-excluding properties, snugly fits upon the foot portion and is preferably vulcanized to the exposed felt or compressible portion thereof, and the upper or ankle portion of the shoe, snugly embraces the 20 lower part or reduced extension of the leg portion and abuts at its upper end against the downwardly-facing shoulder 22 thereof, the contacting portions of the shoe and leg portion being fastened together with a water-proof cement, 25 so that it shall be impossible for water to enter between the upper end of the shoe and the shoulder 22 and thus obtain access to the metal portions and to the cord 39 with the possibility of corrosion of the former and impairment of 30 the efficiency and strength of the latter.

If the wearer happens to step on an uneven or irregular surface, the cushioning body portion of the foot will yield to avoid danger of a fall, and it will yield laterally as well as longitudinally 35 by reason of the ball and socket ankle-joint and the rubber shoe, the latter in conjunction with the cord 39 holding the ankle-joint members against relative dislocation so that no undue play or movement of the foot is permitted. At the 40 same time the ankle-joint parts are held firmly together so as to avoid lost motion and the consequent shock or jar on the stump of the leg in the event the wearer in stepping down or otherwise throws his weight forcibly upon the artificial 45 foot. The rubber shoe not only possesses the advantage mentioned and the other advantage of making the foot waterproof, but also, through its resiliency, assists in restoring the toe portion of the foot to normal position after each bending operation thereof, as it is a common fault of the ordinary compressible foot after absorbing water followed by repeated bending operations, to retain its bent position, which is objectionable from an 50 æsthetic point of view, and also because lacking "life" becomes inefficient in the performance of 55 cushioning functions.

From the above description, it will be apparent that I have produced an artificial leg embodying the features of advantage set forth as desirable 60 in the statement of the objects of the invention, and which is susceptible of modification in various particulars without departing from the principle of construction and mode of operation involved or from the spirit and scope of the appended 65 claims.

I claim:

1. In an artificial limb, a leg portion having a 70 depending portion terminating at its lower end forward of its rear edge in a hemispherical projection, a correspondingly shaped wear plate on said projection and secured in rigid relation thereto, a foot portion having a conforming cavity or depression receiving said projection and a corresponding wear plate lining, a conforming 75 compressible lining interposed between the first-

named and last-named wear plates; the last-named plate having front and rear portions fitting flatly upon the instep and top of the heel portions of the foot and provided with depending flanges engaging the side and rear edges of the foot, a sole plate underlying the rear half of the foot and provided with an upstanding marginal flange externally engaging the sides and rear end of the foot. 80

2. In an artificial limb, a leg portion having a depending hemispherical projection, a correspondingly shaped wear plate thereon, a foot portion having a conforming cavity or depression and a corresponding wear plate lining, and a conforming compressible lining interposed between the first-named and last-named wear plates; said wear plate lining of the foot portion having forward and rearward extensions resting flatly upon the foot portion and provided with a depending marginal flange running around the sides of said extensions and the rear end of the rear extension, a plate underlying the instep portion and heel of the foot portion, a cord extending up through the foot portion and the overlying plate extension and into the leg portion and anchored at its lower end to the plate underlying the foot portion and at its upper end within the leg portion, and a resilient shoe completely encasing the foot portion and said underlying plate and the lower part of the leg portion and offering resistance to downward movement of the latter independent of the foot portion; said shoe being vulcanized to the foot portion and cemented at its upper end, to the leg portion. 90

3. An artificial limb, comprising a lower leg 110 portion and a foot portion having a universal ankle-joint connection, and an upright non-elastic flexible cord connection back of the ankle-joint connection, the foot-portion consisting of compressible material; and a resilient shoe-shaped sheath enclosing the foot portion and the lower part of the leg portion and bearing at its upper end against the latter to yieldingly resist changes of angular relation between it and the foot portion, the cord connection substantially 115 limiting forward bend of the leg portion relative to the foot portion and undue stretching of the resilient shoe or sheath; and a pair of hard-material plates respectively covering the top of the foot portion around the ankle joint connection, 120 and the bottom of the rear half of the foot portion, the last-named plate being connected to and forming a lower anchorage for the cord. 125

4. An artificial limb, comprising a lower leg portion and a foot portion having a universal 130 ankle-joint connection and an upright non-elastic flexible cord connection back of the ankle-joint connection, the foot-portion consisting of compressible material, and a resilient shoe-shaped sheath enclosing the foot portion and the lower part of the leg portion and bearing at its upper end against the latter to yieldingly resist changes of angular relation between it and the foot portion, the cord connection substantially 135 limiting forward bend of the leg portion relative to the foot portion and undue stretching of the resilient shoe or sheath, and a pair of hard-material plates respectively covering the top of the foot portion around the ankle-joint connection, 140 and the bottom of the rear half of the foot portion, the last-named plate being connected to and forming a lower anchorage for the cord, and means for holding the front portion of the last-named plate lightly against the foot portion to 145 150

- protect the underlying portion of the resilient shoe. 80
5. A metal plate of elongated type having a rounded rear end, the plate comprising front and rear portions relatively disposed to form an obtuse angle, the rear portion having an opening and also having a depending semi-spherical socket portion open at the upper side of the plate and disposed in close proximity to the front portion of the plate and forward of said opening, a heel plate below and generally parallel to the first-named plate, and a compressible foot fitting snugly between and secured to said plates and receiving the socket portion of the first-named plate and provided with an opening alined with the opening of the latter. 85
6. The combination of a leg portion of hard material and a foot portion of compressible material, and an universal ball-joint connection between the lower end of the leg portion and the upper part of the foot portion, a top plate fitting flatly upon the top of the foot portion forward, rearward and at both sides of and integral with the socket portion of the joint and provided around its rear end and sides with depending flanges exteriorly engaging the corresponding surfaces of the foot portion, a plate fitting flatly against the underside of the foot portion and provided with upstanding flanges engaging the proximate exterior surface of the heel portion of the foot. 90
7. The combination of a leg portion of hard material and a foot portion of compressible material, and an universal ball-joint connection between the lower end of the leg portion and the upper part of the foot portion, a top plate fitting flatly upon the top of the foot portion forward, rearward and at both sides of and integral with the socket portion of the joint and provided around its rear end and sides with depending flanges exteriorly engaging the corresponding surfaces of the foot portion, a plate fitting flatly against the underside of the foot portion and provided with upstanding flanges engaging the proximate exterior surface of the heel portion of the foot, and a non-elastic cord connection extending through the foot portion and said top plate rearward of said joint and connected to the bottom plate and the leg portion. 95
